[57] CLAIM

The ornamental design for a cord clamp, as shown.

DESCRIPTION

FIG. 1 is an elevational view of one side of the cord clamp showing my new design, the other side being identical thereto;

FIG. 2 is an elevational view of one end of the cord clamp, the other end being identical thereto; and

FIG. 3 is a cross sectional view taken in the direction of the arrows on line III—III of FIG. 2.

Fig. 1.

Fig. 2.

Fig. 3.
